*Primary Examiner—Susan J. Lucas***[57] CLAIM**

The ornamental design for plug connector for optical fiber cable, as shown and described.

DESCRIPTION

FIG. 1 is a front end, left side and top perspective view of a plug connector for optical fiber cable showing my new design;

FIG. 2 is a rear end, right side and top perspective view thereof;

FIG. 3 is a top view thereof;

FIG. 4 is a right side elevation view taken perpendicular to the front end and the rear end;

FIG. 5 is a front end elevation view taken perpendicular to the right side and the left side;

FIG. 6 is a left side elevation view taken perpendicular to the front end and the rear end;

FIG. 7 is a rear end elevation view taken perpendicular to the right side and the left side; and,

FIG. 8 is a bottom view thereof.
